No. 36,629.

Patented November 17, 1903.

UNITED STATES PATENT OFFICE.

CHARLES H. HOWE, OF LEOMINSTER, MASSACHUSETTS.

DESIGN FOR A HAIR ORNAMENT.

SPECIFICATION forming part of Design No. 36,629, dated November 17, 1903.

Application filed June 11, 1903. Serial No. 161,118. Term of patent 7 years.

To all whom it may concern:

Be it known that I, CHARLES H. HOWE, of Leominster, county of Worcester, State of Massachusetts, have invented a new, original, and ornamental Design for a Hair Ornament, of which the following is a specification, reference being had to the accompanying drawings, in which—

Figure 1 is a perspective view of a hair ornament, showing my design; and Fig. 2 is a sectional view thereof, taken on the line 2 2 of Fig. 1 looking in the direction of the arrow.

Having illustrated my design, what I claim as new, and desire to secure by Letters Patent, is—

The ornamental design for a hair ornament as herein shown.

CHARLES H. HOWE.
